UNITED STATES PATENT OFFICE.

CHARLES PAUL KUEHN, OF CHICAGO, ILLINOIS, ASSIGNOR TO A. STEIN & COMPANY, OF CHICAGO, ILLINOIS, A CORPORATION.

BUCKLE.

1,393,143.

Specification of Letters Patent.

Patented Oct. 11, 1921.

Application filed July 18, 1919. Serial No. 311,852.

To all whom it may concern:

Be it known that I, CHARLES P. KUEHN, a citizen of the United States, residing at Chicago, in the county of Cook and State of Illinois, have invented certain new and useful Improvements in Buckles, of which I do declare the following to be a full, clear, and exact description, reference being had to the accompanying drawing, forming a 10 part of this specification.

The present invention has for its object to provide a simple, cheap and effective construction of buckle and the invention consists in the features of novelty hereinafter 15 described, illustrated in the accompanying drawing and particularly pointed out in the claim at the end of this specification.

Figure 1 is a view in front elevation showing a portion of a garment supporter embodying my invention. Fig. 2 is a view in 20 side elevation. Fig. 3 is a detail view showing the clamp lever in open position. Fig. 4 is a detail view on the line 4-4 of Fig. 1. Fig. 5 is a detail view on the line 5-5 25 of Fig. 1.

The invention relates more particularly to that class of adjustable buckles such as are used in hose supporters, suspenders or the like and in which a clamp lever is employed to enable the buckle to be held securely in position after its adjustment has 30 been effected.

A designates the strap of a hose supporter or suspender to which my improved buckle 35 is attached. As shown, the buckle comprises a body portion B that may be made of wire bent to form the lower inwardly turned arms b, the cross bar b' and the upper inwardly turned arms b². To the cross bar b' will be 40 connected the end of the strap A, such end of the strap being formed as a loop to engage the bar b'. The upper arms b² serve as the pivotal supports for the clamp lever C. As shown, this clamp lever is made of sheet 45 metal having arms c bent to encircle the arms b² and having a bent tongue c' the edge of which is preferably serrated to enable it to more effectively grip the strap A. The parts of the buckle thus far described are of 50 usual construction and the mode of operation of this type of buckle will be readily understood by those familiar with this class of devices. The body of the strap A passes between the looped end portion of the strap 55 that encircles the bar b' and when the clamp

lever is turned to the position shown in Fig. 2 of the drawings, the serrated edge portion of the bent tongue c' will engage and grip the strap and hold it against slipping through the buckle. The lower portion of 60 the strap A will serve to hold a hose supporter loop D or similar device of any suitable construction, this hose supporter loop D being shown as provided with an elongated eye portion d to receive a portion of 65 the stocking or other garment to be suspended and with a flexible tab D' carrying at its end a button d² adapted to enter the contracted portion of the eye d and hold the gripped portion of the stocking or other garment 70 therein.

In order to enable the clamp lever C to be conveniently manipulated and swung from the closed position shown in Fig. 1 to the open position shown in Fig. 3, I provide this clamp lever with a small flexible tab E, preferably of leather, and the upper portion of the tab is securely fastened to the under side of the clamp lever C by a part of the metal that is cut out of the clamp lever 80 C. Preferably, the tab E is held in place by stamping from the body of the clamp lever 75 C two prongs c³ between which prongs and the under side of the body of the clamp lever C the upper end of the tab E will be securely held, as clearly shown in Figs. 3, 4 and 5 of the drawing. To attach the tab E to the clamp lever C, the upper portion of the tab will be placed upon the under side of the lever C opposite the 85 opening in that portion of the lever from which the metal forming the prongs has been stamped; and the prongs c³ will then be firmly pressed toward each other and against the under side of the tab E, causing the tab to be securely gripped between the prongs and the under side of the clamp lever. The pressure exerted upon the prongs in forcing them to the closed position will slightly compress the upper portion of the 90 tab into the opening formed in the clamp lever and this will aid in more effectively holding the tab in place.

My invention presents the first instance, as far as I am aware, of a buckle of the character described having a flexible tab by which it can be manipulated, said tab being connected to the clamp lever of the buckle by a part of the metal stamped from said clamp lever and serving to hold the flexible 105 110

tab in place, and within the scope of the invention, the details of construction may be varied. Thus, for example, instead of two prongs c^3 , a single prong might be used.

5 Having thus described my invention, what I claim as new and desire to secure by Letters Patent is:—

A buckle of the character described, comprising the combination with a body portion, of a clamp lever having a transverse

slot, the metal removed in forming said slot being divided to form separate tongues and being pressed backward from the face of the clamp lever, and a depending flexible pad having its upper portion arranged against 15 the back of said clamp lever and held between said slot and the metal tongues displaced in forming said slot.

CHARLES PAUL KUEHN.
